(57) **CLAIM**

The ornamental design for a fishing rod case, as shown and described.

DESCRIPTION

FIG. 1 is a right elevational view of a fishing rod case showing our new design;

FIG. 2 is a left elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is an isometric view of a fishing rod case illustrated in open position for clarity.
